CLAIM

The ornamental design for a handle for a knife, as shown and described.

DESCRIPTION

FIG. 1 is a front view of a handle for a knife in accordance with the present invention;

FIG. 2 is a back view of the handle of FIG. 1;

FIG. 3 is a side view taken on the left side of FIG. 1 of the handle of the present invention;

FIG. 4 is a side view taken on the right side of FIG. 1 of the handle of the present invention;

FIG. 5 is an end view of the handle of the present invention adjacent to the hilt of the knife blade; and,

FIG. 6 is an end view of the handle opposite the hilt of the knife blade.

The knife blade, which is shown in broken lines in the Figures, forms no part of the present invention and is only to show the environment of the use of the handle of the present invention.
